UNITED STATES PATENT OFFICE.

REGNIER EICKWORTH, OF DORTMUND, GERMANY.

GAS BURNER.

Application filed August 5, 1927, Serial No. 210,796, and in Germany August 6, 1926.

Gas burners are known with which the gas under pressure drives a ventilator wheel which draws in the combustion air and forces it into the combustion chamber. The invention relates to a new burner of this kind which, contrary to the known burners, is also adapted for burning high-grade gases, for instance, coke oven gases.

According to the invention, the gas after being partially deprived of its pressure is conducted through a passage to a mixing chamber in order to deliver the air, the delivered air flowing into said mixing chamber through an independent passage. The gas and air streams are, therefore, subsequently mixed in a suitable manner quite independently of the delivery device, and conducted to the combustion chamber. This makes it possible to effect the delivery of air by means of the energy contained in the gas, even when high-grade gases are burnt, and consequently to secure an automatic regulation of the burner without danger of the flame being forced back against the wheel and destroying the device.

The front portion of the air passage, or of the gas passage, may be used as a mixing chamber. In order to obtain a certain degree of mixing, exchange apertures may be arranged in the division wall between the two passages through which gas reaches the air passage, or air reaches the gas passage. The portions of the burner facing the combustion chamber may be provided with a device for water cooling. Especially a conical hollow body connected to the water main may preferably be arranged in front of the center portion of the wheel for protecting the wheel against the reacting heat, and deflecting the air stream to the side of the gas stream.

In the drawings, various constructions of the burner are shown,

In the drawings—

Fig. 1 is a longitudinal section,

Fig. 2 is a cross section through one portion of the burner,

Fig. 3 is a longitudinal section of another construction,

Fig. 4 is a longitudinal section through a burner with water cooling, and

Fig. 5 is a cross section of the above.

With the burner according to Figs. 1 and 2, a wheel 3, provided with gas inlets 2, and carrying the ventilator blades 4 and the turbine blades 5, is disposed in front of the

annular gas chamber. The gas under pressure flows through the nozzles 10 to the blades 5, imparting rotation to the wheel, the result being that air is drawn through the ventilator wheel 4 through the chamber 12 in the known manner. According to the invention, gas and air are independently conducted at the rear of the wheel into a mixing chamber. The air flows through the duct 6 and the gas through the annular passage 7. In order to obtain a certain degree of pre-mixing, the duct 6 may be provided with exchange apertures 8 through which air may enter into the gas passage, or gas into the air passage. The adjustable cover 9 serves for regulating the entry of air.

The chamber 12 is in the form of a central opening in the casing 1, which has an annular chamber surrounding the opening 12. From this annular chamber, to which the gas inlet 2 leads, the nozzles 10, provided in the wall of the casing, direct the gas against the outer vanes 5 to turn the wheel 3, and thus cause the blades or vanes to draw in air through the inlet opening 12. The casing is extended forward enveloping tubular member 6, and providing the passage 7, this passage contracting because the forward extended part of the casing 1 converges with respect to the member 6.

With the construction of the burner according to Fig. 3, the inner duct 6 is made shorter than the outer duct 11 so that the end of the outer duct serves as a mixing chamber.

With the construction according to Figs. 4 and 5, a conical hollow body 13 is disposed at the mouth of the inner duct 6 which deflects the air in the direction of the gas passage, thus protecting the wheel against the radiating heat. Similarly an annular hollow body 14 is disposed in front of the outer duct. The two inner spaces 15 and 16 of these bodies communicate through the duct 17. The cooling water first enters the hollow body through the connection 18, whence it flows through the duct 17 into the outer annular body 14 and then away through the connection 19.

I claim:

1. A burner comprising a casing having a central air inlet and an annular gas chamber therein surrounding said central air inlet, said chamber having nozzles through which gas may issue, a wheel having an outer series of vanes adjacent said nozzles and an

inner series of vanes adjacent said inlet whereby gas acting upon the outer series of vanes may turn said wheel to draw air through the inlet, and a tubular member in line with said inlet within the casing, the casing being extended to envelop said member, providing an annular passage between said member and the extended portion of the casing through which the gas is impelled,
10 the air and gas mixing after the air enters the said member.

2. A burner comprising a casing having a central inlet opening and containing an annular chamber to which gas is admitted, a
15 wheel having a series of blades in line with

said opening, and a second series of blades surrounding the first series, the casing having nozzles through which gas issuing from said chamber may be directed against said second series of blades, a tubular member in line with said inlet in which air is impelled by the first series of blades, the casing being extended to envelop said member, a hollow body adjacent the end of said member, and means for admitting a cooling fluid to said body and conducting it therefrom.
